UNITED STATES PATENT OFFICE.

EDGAR FORREST SCALES, OF DANVILLE, VIRGINIA.

AUTOMATIC ALARM FOR SATCHELS.

Application filed November 6, 1925. Serial No. 67,416.

This invention relates to alarm means for satchels, the general object of the invention being to provide means for sounding an alarm when the satchel is picked up by its handle by a thief or other unauthorized person, with means for preventing the operation of the alarm when the owner desires.

Another object of the invention is to provide combination keys for rendering the device operative and inoperative, said keys being arranged in the handle.

A further object of the invention is to so arrange the parts that the alarm cannot be stopped or turned off until the satchel is opened.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a view of a satchel provided with my invention, with parts broken away.

30 Figure 2 is an enlarged sectional view through the handle and one of the angle bars of the satchel.

Figure 3 is a section on line 3-3 of Figure 2.

35 Figure 4 is a similar view, but showing the yoke member in a different position.

Figure 5 is a section on line 5-5 of Figure 2.

40 Figure 6 is a section on the line 6-6 of Figure 2.

Figure 7 is a section on line 7-7 of Figure 2.

Figure 8 is a section on line 8-8 of Figure 2.

45 Figures 9 and 10 are views of the combination keys.

As shown in Figure 1, I place an electric horn 1 or other alarm on a perforated plate 2 which covers an opening 3 formed in the bottom of the satchel, and this alarm is connected by the conductor 4 with a battery B and by the conductor 4' with a terminal 5 on one of the angle bars 6 of the satchel. A conductor 4^x connects the battery with a switch arm 7 which is connected by a bolt 8 with a block 9 of insulating material fas-

tened to said angle bar. The stationary part 10 of the switch is also mounted on said block but is electrically connected with the angle iron by the bolt 11. Thus when the switch arm 7 is in contact with the part 10, the circuit to the alarm will be closed and the same will be sounded. A spring 12 on bolt 8 frictionally holds the switch arm in adjusted position and said arm is provided with a projection 13.

The handle 14 of the satchel is of hollow construction and has one end flexibly connected to the angle bar 6 by the screw 15 so that the other end can be lifted from the angle bar, this lifting movement being limited by the screw 16 inserted in said end and passing through a hole in the angle bar. Thus when the handle is grasped, the screw 15 will bend enough to permit the end of the handle which carries the screw 16 to raise off the angle bar 6 until the head of the screw 16 engages said bar. A spring 17, inserted in a socket in the handle and engaging the angle bar 6, tends to hold the opposite end of the handle against said bar, as shown in Figure 2. The handle is preferably formed of two halves which are fastened together by the bolts 18.

50 A yoke member 19 is pivoted in the handle by the pins 20 engaging the limbs of the member so that said member has rocking movement, and one limb is extended, as at 21, to pass through a hole in the bar 6 into the satchel. A long pin 22 is fastened to this extended part. When the yoke member has not been tilted, the pin 22 is in engagement with the projection 13 of the switch arm so that when the handle is lifted, the movement of the yoke member and pin will swing the switch arm upwardly against the contact 10 and thus close the circuit to the alarm, and it will be seen that the switch arm will remain in engagement with the part 10 to keep the circuit closed even after the handle has been released and the spring 17 has returned the parts to normal position. The alarm will therefore continue to sound until the satchel has been opened and the switch arm moved to open position by hand.

55 In order to prevent the closing of the circuit when the satchel is being used by the owner or other authorized person, I provide a key 23 arranged in the handle and having a beveled part 24 at its lower end for engaging a rigid part 19' of the yoke

member, so that when said key is depressed, the yoke member will be rocked on its pivot to the position it occupies in Figure 4, where a latch member 25 on the bar 6 will engage 5 a keeper recess 27 on the extended part 21 of the yoke member which will prevent movement of the handle when the same is lifted. As soon as the handle is released, a spring 28 will throw the yoke member back to its 10 normal position. Other keys 29 are arranged in the handle, but the beveled portions 30 of these keys are so arranged as not to move the yoke member when they are depressed. A spring bar 31 in the handle and 15 passing through all the keys, serves to hold the keys in raised position.

From the foregoing, it will be seen that unless the key 23 is depressed before picking up the satchel by its handle, the handle 20 will be tilted as soon as the satchel is raised so that the yoke member will move the switch arm to closed position by its pin 22 so that the alarm will sound and will continue to sound until the satchel is opened 25 and the switch arm moved to open position by hand. However, when the key 23 is depressed, the yoke member is swung over to engage the latch which will prevent the handle from tilting when the satchel is 30 raised so that in this case the alarm will not be sounded. By having a plurality of keys, a person will not be likely to find the proper key unless he knows the combination.

The invention is mainly designed for 35 satchels used by bank runners and persons carrying valuables.

It is thought from the foregoing description that the advantages and novel features of my invention will be readily apparent.

I desire it to be understood that I may make changes in the construction and in the combination and arrangement of the several parts, provided that such changes fall within 45 in the scope of the appended claims.

What I claim is:

1. In combination with a satchel, a handle thereon, means for permitting limited vertical movement of the handle, an alarm 50 in the satchel, a circuit for the same including a switch arranged within the satchel, means operable by the vertical movement of the handle with reference to the satchel for closing the circuit and means for preventing vertical movement of the handle when desired.

2. In combination with a satchel, a handle thereon, means for permitting limited vertical movement of the handle, an alarm

in the satchel, a circuit for the same including a switch arranged within the satchel, means operable by the vertical movement of the handle with reference to the satchel for closing the circuit and combination lock means for preventing vertical movement of the handle when desired. 60 65

3. In combination with a satchel, a handle, means at one end of the handle for flexibly connecting it with the satchel, means at the other end for limiting the vertical movement of the handle, spring means for holding the handle in normal position, an alarm in the satchel, a circuit therefor including a switch within the satchel, a member carried by the handle and having a part extending within the satchel for closing the switch when the handle is moved vertically with reference to the satchel, means for preventing vertical movement of the handle when desired. 70 75 80

4. In combination with a satchel, a handle, means at one end of the handle for flexibly connecting it with the satchel, means at the other end for limiting the vertical movement of the handle, spring means for holding the handle in normal position, an alarm in the satchel, a circuit therefor including a switch within the satchel, a member carried by the handle and having a part extending within the satchel for closing the switch when the handle is moved vertically with reference to the satchel, means for preventing vertical movement of the handle when desired, and means for holding the switch closed after once being closed 85 90 95 so that the satchel can be opened and the switch opened by hand to break the circuit.

5. In combination with a satchel, a handle, means for flexibly connecting one end of the handle to the satchel, means for limiting the movement of the other end of the handle, an alarm in the satchel, a circuit therefor including a switch in the satchel, a member having a part extending within the satchel, means for connecting the member with the handle so that the said member has rocking movement, a projection on said extended part for engaging the switch to close the same when the handle is moved vertically with reference to the satchel, a latch in the satchel for engaging a part of the extension when the member is rocked to prevent vertical movement of the handle, a key in the handle for rocking the member and other keys in the handle for forming the combination means with the first key. 100 105 110 115
